BUILDING BLOCK

Arthur E. Troiel, Berkeley, Calif.

Application November 26, 1935, Serial No. 51,630

3 Claims. (Cl. 46—26)

This invention relates to building blocks, and especially to blocks for the instruction and entertainment of children.

It is the object of the present invention to provide an attractive, inexpensive and durable set of blocks or building units capable of being securely locked together by simple connecting members and without the use of tools to form rigid structures of various shapes, the blocks being so designed that a relatively small number of blocks may be employed in setting up a great variety of structural shapes.

My invention consists essentially of blocks of wood or the like that are slotted in a uniform manner for the reception of metal connecting members. The connecting members are designed to slip into the slots of the blocks in various positions and combinations of positions to make possible the fabrication of rigid structures that are easily assembled and may be readily disassembled, when desired, without in any way defacing any of the building units.

One form of my invention is exemplified in the accompanying drawings, and further of its objects and advantages are made apparent in the following specification, wherein reference is made to the drawings.

In the drawings—

Fig. 1 is a perspective view of a corner of a building constructed of blocks made in accordance with my invention and showing typical uses of various shapes and sizes of blocks and connecting members;

Fig. 2 is a perspective view of a single block, showing in detail the manner in which the blocks are slotted for the reception of connecting members;

Figs. 3, 4, 5, 6 and 7 are perspective views of various types of connecting members for locking together blocks such as that disclosed in Fig. 2;

Figs. 8, 9, 10, 11 and 12 are perspective views of blocks and connecting members illustrating typical uses of the different types of connecting members for securing the blocks in various positions relative to each other;

Fig. 13 is a perspective view of a stack of blocks, showing a clip member and illustrating the manner in which such member may be used to prevent separation of the blocks in a vertical direction.

Referring more particularly to the drawings, a typical block is illustrated at 10 in Fig. 2. The blocks 10 are formed of standard thickness and have a width double their thickness and may be

of lengths varying in increments of their thickness. For example, if the blocks are one inch thick they will be two inches wide and two, three, four or five inches, etc., long up to any desirable maximum length.

While these proportions are desirable and the above stated dimensions have been found convenient to form a small set of building blocks, it will, of course, be understood that the dimensions may be increased or decreased to form blocks of any size while the general proportions are maintained. For simplification of the description the size of the blocks will be assumed, as stated above, as 1" x 2" in cross section.

Each block is slotted in accordance with a uniform plan. The slots may be saw kerfs which are simply and inexpensively produced with a motor driven circular saw. For blocks of this size I have found that slots slightly less than $\frac{1}{8}$ " in width are desirable as metal connecting members of this thickness are sufficiently strong, and the slots are not large enough to deface the blocks or hinder the appearance of a finished structure built with them.

A desirable arrangement of slots is illustrated in Fig. 2 where the ends of the block are shown as provided with crossed slots 11 and 12 at right angles to each other and equally spaced from the edges to which they are parallel. Still assuming the cross section of the blocks to be 1" x 2", the block ends will be divided by these slots into sections approximately $\frac{1}{2}$ " x 1". Slots 13, cut centrally of the edges of the blocks and extending throughout their length, connect the end slots 11 and a slot 14, formed on one face of the block, connects the end slots 12. On the edges 15 slots 16 are cut $\frac{1}{2}$ " from the ends 17 of the blocks. These slots are parallel to the ends of the block and cooperate with the slot 13 to divide the end portions of the edges 15 into two $\frac{1}{2}$ " squares. Any side of one of these squares is equal to one-half the thickness of a block. Consequently, the slots in adjacent blocks will align when the blocks are placed end to end, as illustrated in Fig. 8, when the blocks are overlapped 1" or the distance of their thickness, as illustrated in Fig. 9, or when they are arranged to form a right angular corner, as illustrated in Fig. 10. This makes possible the use of the connecting members presently to be described for connecting or locking the blocks to each other in a large variety of different positions.

The connecting members illustrated in Figs. 3 to 7, inclusive, are preferably formed of metal, but may be made of any suitable material that is suf-

ficiently strong and rigid to serve their purpose. In Fig. 3 I show a small substantially square metal plate 18, which I prefer to term a single-slot bar, having a slot 19 formed therein midway between two parallel edges. The thickness of the member 18 is such that it will slip into the slots formed in the blocks and the width of the slot 19 is sufficient to receive a member of the same thickness.

10 In Fig. 4 I show a three-slot bar 20, similar in dimensions to the single slot bar 18 except that it is longer and differing also in that it is provided with three slots 21 equally spaced along one of its edges, the spacing between the slots being approximately one-half inch.

15 Fig. 5 illustrates a connecting member that will be referred to as an L-bar 22, having a slot 23 spaced approximately one-half inch from one end and having a half inch square cut from its

20 opposite end, leaving connected to the bar an ear 24, bent at right angles to the bar 22. The connecting member, illustrated in Fig. 6, is termed a Z-bar 25 and is similar in dimensions to the other connecting members but is provided 25 with half inch square ears 26 at opposite ends and bent at right angles to the plane of the main portion of the bar. Tension bars 27, such as illustrated in Fig. 7, may be provided in any desired length. These bars are formed of metal

30 just one-half of the thickness of the metal from which the other connecting members are formed so that they may overlap each other within a slot in the block. One edge of each tension bar 27 is provided with equally spaced slots 28 throughout its length. A row of perforations 29 is provided along the same edge, the perforations being formed in the metal between the slots 28 and a similar row of perforations 30 being formed along the opposite edge of the tension bar.

35 Some typical uses of the connecting members above described are illustrated in Figs. 8 to 12, inclusive, of the drawings.

40 In Fig. 8 two of the blocks 10 are secured in position with their ends in abutment by means of a Z-bar 26. In this use of the Z-bar the main portion of the bar is inserted in the aligning slots 13 of the blocks 10 and the ears 26 of the bar are received by the slots 16. This forms an interlocking connection between the blocks maintaining close contact between their abutting ends 45 and substantially preventing twisting or turning relative to each other in any direction. The Z-bar, as is true of all of the connecting members, has a width substantially twice the depth of the 50 slots formed in the blocks, and consequently one-half of the bar projects upwardly from the blocks, as illustrated, in a position to receive the slots 13 of other blocks which will be laid on edge on top of the blocks 10 in the construction of a wall or 55 the like.

60 In Fig. 9 the Z-bar is illustrated in a position ready for insertion into the slots of a pair of blocks that are overlapped to form a jog or step in the side of a wall. In this position the main portion of the Z-bar is disposed transversely to the blocks and will be inserted into the aligning slots 16 while the ears 26 will be received by the longitudinally extending slots 13.

65 Fig. 10 illustrates a pair of the blocks 10 arranged to form a corner, with one end of one block abutting a side of the other block so that the slot 13 of the first block aligns with the slot 16 of the second block. This figure also illustrates the manner in which an L-bar 22 and a 70 three-slot bar 20 may be combined to securely

lock the blocks together in this position and present an upwardly extending edge by means of which the next tier of angularly disposed blocks will be supported in proper position. The L-bar 5 22 is positioned at right angles to the three-slot bar 20. These two connecting members are interlocked with each other by means of their respective slots 23 and 24. The ear 24 of the L-bar will be received by the slot 16 in a block 10 and the main portion of the bar will fit into the slot 10 13 of the same block and extend into the slot 16 of the next block. The three-slot bar is received by the slot 13 of the latter block and after the connecting members have been inserted in the proper slots their upwardly projecting portions 15 will form a cross at the corner which will be received by the slots of the next adjacent tier of blocks to support them in a position of alignment with the first tier.

Fig. 11 illustrates one manner in which blocks 20 18 may be connected with their ends in abutment when it is desired that the connection be made without any of the connecting members exposed to view. In this figure a three-slot bar 20 and a single slot bar 18 are combined with their slots 25 21 and 19 in register to form a cross. This cross is insertable into the end slots 11 and 12 of adjacent blocks to maintain them in alignment with each other.

When two or more of the blocks 10 are to be 30 supported in end-to-end alignment to form a beam in which more or less tensile strength is necessary or desirable, tension bars of the type illustrated in Fig. 7 may be used. If a length greater than that presented by a single tension 35 bar is needed two or more bars may be overlapped at their ends, as illustrated in Fig. 12. The tension bars are received by the slots 13, formed in the edges of the blocks and any number of blocks of random length may be combined to form a 40 tension bar having the required length.

45 In Fig. 12 I have illustrated the use of single slot bars 18 interlocked with the tension bars at intervals to be received by the slots 16 of the blocks 10. This will retain the blocks against longitudinal sliding movement on the tension bars and will add to the tensile strength of the made-up beam where two or more tension bars are combined to obtain exceptional length. In the event that unusual strength is necessary in 50 the beam small rivets or pins 35 may be inserted through aligning perforations in the tension bars to insure against sagging of the beam.

55 While in most instances these pins will not be necessary, it has been found that by merely slipping them through aligning perforations in the bar additional rigidity is obtained and it is unnecessary that they be peaned over or otherwise secured in the bar, as they are substantially the same diameter as the perforations and are held 60 in place by friction sufficiently for ordinary purposes and yet may be easily removed when the structure is being disassembled.

When the blocks are superposed to form a wall in the manner illustrated in Fig. 13, their end slots 65 11 will be in alignment and through the use of tension bars 27 and single-slot bars 18 interlocking with the tension bars and received by the slots 12 in the ends of the blocks vertical separation may be prevented. In some instances, however, the ends of the blocks will not be accessible as they are illustrated in Fig. 13 and in order to prevent vertical separation of the blocks and to provide a structure that may be easily transported 70 from place to place without danger of its coming 75

apart I have provided clips 44, which consist of metal bands having their ends 45 bent at right angles for reception by the slots 14 in the sides of the blocks. These clips 44 may be of various lengths to hold any number of blocks together; the one illustrated in Fig. 13 being of a suitable length for three blocks. If desired, the ends 45 of the clips may be bent at slightly more than a right angle so that it will be necessary to force them into the slots 14, and with this arrangement the resiliency of the clip will prevent its being dislodged as the structure is moved from place to place.

Referring now to Fig. 1 of the drawings, I illustrate a small portion of a structure being erected with the blocks and connecting members above described. In this view blocks 10 of various lengths are illustrated as forming a foundation by being placed on edge. It is obvious that blocks 20 in the same position superimposed on this foundation will make a continuous wall. Where it is desired that windows and doors be provided in the wall the same blocks may be used on end as illustrated. These blocks are held against being dislodged as their end slots receive the upwardly extending portions of connecting members which are employed for interlocking the foundation blocks. For simulating vertical posts of smaller dimensions blocks, such as that illustrated at 36 30 in Fig. 1, are provided. These blocks are square in cross section and are provided with longitudinally extending slots 37 along opposite sides which are also continued across their ends where they are crossed by transverse slots 38.

For providing arched windows or doorways blocks having one corner cut away arcuately are employed, as illustrated at 39. Blocks of the type illustrated at 38 are provided in various lengths to be interposed between the arch blocks 39 so that the window or door openings may be of any width desired. Moulding cutters may be employed to dress the edges of the blocks 38 and 39 to lend a finish and decorative effect to the windows and doorways. Floors and ceilings or the like may be built up of the standard blocks 10, which may be supported relative to each other and relative to the structure itself by means of the tension members 27 and three-slotted bars 20 registering with the slots 11 and 13 of the blocks forming the floor, and with the slots 14 of the foundation or other portions of the structure. Gable blocks of the type illustrated at 40 and 41 50 are provided for fabricating roofs or other surfaces disposed at an angle to the main structure.

These gable blocks are slotted in a manner similar to that described for the blocks 10 but are provided with additional slots 43 parallel to their angular edges and spaced approximately one-half inch from said edges. These slots serve 5 to support a roof built-up of blocks 10 in the same manner that the floor illustrated in Fig. 1 is built up and supported.

Blocks of other shapes may be provided for ornamenting structures fabricated with the simpler 10 forms of blocks described.

While I have, for the purpose of illustrating my invention, shown but a few blocks and connecting members of simple design and illustrated a limited number of combinations in which these members may be employed it is of course to be understood that various changes may be resorted to in the design, construction and arrangement of the several parts within the scope of the appended claims.

Having thus described my invention, what I claim and desire to secure by Letters Patent is:—

1. In combination with building blocks slotted for the reception of connecting members, flat metallic tension members comprising elongated strips insertable in aligned slots of two or more adjacent blocks, said tension members being of a thickness permitting their overlapping within the slots of the blocks.

2. A set of building blocks comprising rectangular block members slotted on their edges and sides, slotted interlocking connecting members cooperating with the edge slots of the blocks to retain them in position with their edges abutting to form wall structures, and clip members comprising flat bands with right-angularly bent ends 30 engaged with the side slots with the bands disposed flat against the side walls of the blocks to prevent separation of the blocks forming the 35 wall structure.

3. In combination with building blocks slotted for the reception of connecting members, tension members comprising elongated strips insertable in aligned slots of adjacent blocks, said tension members being slotted for interlocking engagement with connecting members disposed at right angles to the tension members, and said tension members being of a thickness permitting them to overlap within the slots of the blocks whereby the two tension members may be locked against 45 relative longitudinal movement by said connecting members.

ARTHUR E. TROIEL.
